(57) **CLAIM**

An ornamental design for a skull light, as shown and described.

DESCRIPTION

FIG. 1 is a front, top and left side perspective view of a first embodiment of a skull light showing my new design, as adapted to be a side-mounted skull signal light;

FIG. 2 is a front elevational view thereof;

FIG. 3 is a rear elevational view thereof;

FIG. 4 is left side elevational view thereof;

FIG. 5 is right side elevational view thereof;

FIG. 6 is a top plan view thereof;

FIG. 7 is a bottom plan view thereof;

FIG. 8 is a front, top and left side perspective view of a second embodiment of a skull light showing my new design, as adapted to be a trailer hitch-mounted skull signal light;

FIG. 9 is a front elevational view thereof;

FIG. 10 is a rear elevational view thereof;

FIG. 11 is left side elevational view thereof;

FIG. 12 is right side elevational view thereof;

FIG. 13 is a top plan view thereof; and,

FIG. 14 is a bottom plan view thereof.

The broken lines shown in the drawings represent environmental subject matter and form no part of the claimed design.

The dot-dashed broken lines shown in the drawings illustrate boundaries of the claimed design and form no part thereof.

1 Claim, 10 Drawing Sheets
